UNITED STATES PATENT OFFICE.

CARL OTTO, OF HELLERUP, DENMARK.

REGENERATIVE COKE OVEN.

Application filed April 25, 1925, Serial No. 25,783, and in Germany June 26, 1924.

My invention relates to a regenerative coke oven with a series of alternate horizontally elongated oven chambers and heating walls therefor, arranged side by side, each of 5 said heating walls comprising vertical combustion flues, and in which the regenerators are arranged beneath the oven soles in the direction of the oven chambers.

In accordance with the invention, I obtain 10 the advantage of arranging the heating walls in pairs at the same time maintaining the advantage of providing a large number of regenerators for the heating flues, thus permitting improved regulation.

15 In accordance with the invention, the heating flues of two even-numbered or alternate heating walls and two odd-numbered or intermediate heating walls are directly connected by cross-over conduits each of 20 which runs over two oven chambers so as to connect the said walls into single independent pairs and moreover the regenerators of an even-numbered pair of walls are combined with the regenerators of an odd-numbered 25 pair into a single heating unit. By this means the heating of an entire heating wall takes place by the flow of heat in the same direction by means of subdivided groups or separated systems of heating flues, 30 heating gas and air for combustion being supplied to each heating system in regulated amounts, and two symmetrical or like heating systems, each in a separate heating wall, are connected by a cross-over conduit in the 35 oven top.

The invention may be applied to regenerative, horizontal coke ovens of either the front flue supply, in which the flues are supplied with rich gas from the fronts of 40 the oven, or of the underburner type in which rich gas is supplied from passageways underneath the oven.

When the invention is applied to underburner coke ovens the regenerators run 45 lengthwise of the oven chambers and are arranged between the sole of the oven chambers and the ceilings of the accessible passageways underneath the oven, the oven being supported above the ground and the passageways permitting access to the valves 50 for regulating the rich gas supply.

With the underburner oven constructed 55 as above, gas leakage is reduced, the strong gas being supplied to the flues thru pipes forming part of the underburner system.

With the above and other objects in view,

my invention consists in the parts, improvements and combinations more fully pointed out hereinafter.

Turning now to the drawings:

Figure 1, is a cross-sectional view of a horizontal, regenerative coke oven fed by strong gas and weak gas from the oven fronts, with alternate heating walls connected by cross-over conduits.

Figure 2, is a cross-sectional view running crosswise of the oven chamber of an underburner oven, showing alternate heating walls connected at the tops and strong gas fed from the passageways below the oven, and

Figure 3, is a cross-sectional view across the oven chambers, in which weak gas or weak gas and strong gas may be supplied to the flue systems of an underburner oven, alternate heating walls being connected at 75 the tops by cross-over conduits.

Figure 4, is a cross-section through the heating wall 1, running longitudinally thereof.

In accordance with the drawing, Figure 80 1, the heating wall 1, is connected with the heating wall 3, by several conduits 5, and the heating wall 2, is connected with the heating wall 4, by several conduits 6. Heating flues in two alternate heating walls only are thus 85 directly connected together at one end of said flues by their respective cross-over conduits. The direction of flow of the air, the weak gas, the burning gases and the waste heat for one period of oven operation is indicated by the arrows. On reversal, the flow 90 is reversed. Each of the conduits 5, and 6 are separate and independent and pass over two oven chambers 7, which lie respectively between the ends of the conduits. The re- 95 generators belonging to the heating walls are so arranged and combined that regenerators 8, 9, serve for preheating the air and regenerators 10, serve for the preheating of gas, if the oven is being heated by weak gas.

100 All of these regenerators serve for preheating the air when the oven is heated by strong gas, separately supplied thru pipes 11, each pipe 11, being connected to the respective flues of the heating wall. When regenerators 8, 10, 9 connected to the flues of successive walls 1, 2 are being used to preheat air or air and gas, regenerators 12, 13, 14 connected to the flues of successive walls 3, 4, receive the off-heat. By reason of this 110 combination of regenerators and heating flues, each two pair of heating walls form a

heat unit and in the best embodiment of the invention the direction of flow is so arranged that the flow takes place in opposite directions in the upper cross-over conduits of two neighboring heating units. By this means one obtains the great advantage that the direction of flow is the same in six adjacent regenerators. In other words, an opposite direction of flow between adjacent air and waste-heat regenerators occurs only at each fifth heating wall.

In Figure 1, the oven is shown as heated with weak gas and strong gas. If it is desired to heat with strong gas alone, either all of the regenerators may be used for pre-heating air or some of the regenerators may be omitted, each of the remaining regenerators supplying preheated air to the flues of two adjacent heating walls.

Turning now to Figure 2, the direction of flow of air, burning gases and waste heat, is indicated by arrows. Oven chambers 15, are provided with heating walls 16. In each heating wall one or more systems of heating flues are provided, the burning gases flowing in the same direction in the flues of any one heating system. The flue systems of the heating walls are numbered respectively, 17, 18, 19, 20, 21, 22, 23, 24. Each flue system comprises a plurality of flues extending side by side along the heating wall and the flues of the respective systems communicate at the tops or ends by means of horizontal channels 25, 26, 27, 28, 29, 30, 31, 32. Separate cross-over conduits 33, 34, 35, 36, communicate with alternate channels and thus separately connect alternate systems of flues, that is to say, the like flue systems of alternate heating walls are so connected. Conduit 33, connects flue system 17, with flue system 19, conduit 34, connects flue system 18, with flue system 20, conduit 35, connects flue system 21, with flue system 23, and conduit 36 connects flue system 22, with flue system 24.

In Figure 2, strong gas is supplied to each flue of a flue system by means of pipes 37, 38, 39, 40, 41, 42, 43, 44, there being a series of pipes for a flue system, a separate pipe for each flue of the system. These pipes run from the underburner passageways 45, underneath the oven, the oven being supported above the ground upon posts 46. Preheated air is supplied to the flue systems by regenerators 47, which extend below the oven chamber soles in the direction of the oven chambers, and communicate with the flue systems by passageways 48, there being one air passageway for each flue of a system.

It will be observed that in the form of the invention illustrated in Figure 2, in each four regenerators arranged side by side in a group, the direction of flow of waste heat or of preheated air is in the same direction, by means of which the considerable advan-

tage is realized of reduction of leakage between regenerators, such as would occur if the direction of flow in adjacent regenerators were in opposite directions.

In the form of the invention illustrated in Figure 3, the coking chambers 49, the heating flue systems 50, 51, 52, 53, 54, 55, 56, 57, of the heating walls 58, and the cross-over conduits 59, 60, 61, 62, are constructed and arranged as in Figure 1, but the oven may also be heated by weak gas. This preheated weak gas is supplied by regenerators 63, weak gas being supplied to the regenerators by pipes 64. Preheated air is then supplied by regenerators 65. Strong gas may also be used instead of weak gas by means of pipes 100, there being one strong gas pipe for each heating flue of a flue system. When strong gas is used preheated air may be supplied by regenerators 63 and regenerators 65. Air is supplied to regenerators 65, and 63, thru conduits 66, running underneath the regenerators to the fronts of the oven. The respective regenerators are connected to each of the heating flues by passageways 67, 68. In the form of the invention illustrated in Figure 3, the flow of waste heat is in the same direction in eight of the neighboring regenerators and the flow of weak gas and air is likewise in a common direction in another eight neighboring regenerators. Leakage between regenerators of a group in which the direction of flow is the same, is accordingly avoided.

It will be understood that the drawings show a one period operation of the oven and that upon reversal of the oven, the flow of weak gas, and air and the waste heat in Figure 3, is reversed. The flow will then take place in directions indicated by reversing the arrows in this figure. The ovens of Figures 1 and 2 may, likewise, be reversed.

Having thus described the invention and its operation, it will be understood that changes may be made in construction and arrangement of the flues without departing from the principle of the invention.

What I claim is:

1. A regenerative coke oven which may be heated as desired by strong gas or weak gas, provided with a series of alternate horizontally elongated oven chambers and heating walls therefor, arranged side by side, each of said heating walls having vertical heating flues, cross-over conduits, each connecting together the tops of flues of alternate heating walls only, into independent flue systems, regenerators extending longitudinally of the oven chambers and connected to the flue systems for preheating air and for receiving waste heat therefrom, and means for supplying strong gas to the flues of the flue systems.

2. A regenerative coke oven which may be heated as desired by strong gas or weak gas,

provided with a series of alternate horizontally elongated oven chambers and heating walls therefor, each of said heating walls having vertical heating flues, cross-over conduits, each connecting together the tops of flues of alternate heating walls only, into independent flue systems, and regenerators extending longitudinally of the oven chambers and connected to the flue systems for pre-heating air and gas for and receiving waste heat from said flue systems.

3. A regenerative coke oven which may be heated as desired by strong gas or weak gas, provided with a series of alternate horizontally elongated oven chambers and heating walls therefor, each of said heating walls having vertical heating flues, cross-over conduits, each connecting together the tops of flues of alternate heating walls only, into independent flue systems, regenerators extending longitudinally of the oven chambers and connected to the flue systems for pre-heating air and gas for and receiving waste heat from said flue systems, and separate means for supplying strong gas to each of the flues of the flue systems.

4. A regenerative coke oven which may be heated as desired by strong gas or weak gas, provided with a series of alternate horizontally elongated oven chambers and heating walls therefor, each of said heating walls having vertical heating flues, regenerators for air and gas connected to said heating flues and separate cross-over conduits, passing over the tops of the coking chambers, which directly connect heating flues of one wall with flues of an alternate wall only of the series, so that two even-numbered heating walls and two odd-numbered heating walls are each connected into a pair, said pairs and the regenerators connected thereto being connected into a single heating unit.

5. A regenerative coke oven which may be heated as desired by strong gas or weak gas, provided with a series of alternate horizontally elongated oven chambers and heating walls therefor, each of said heating walls having vertical heating flues, separate cross-over conduits directly connecting flues of alternate heating walls only, more than two regenerators extending longitudinally of and below the oven chambers for preheating air, separate means for supplying gas to each of the flues and means for connecting the regenerators with flues of successive heating walls, so that the flow in more than two adjacent regenerators may be in the same direction simultaneously.

6. A regenerative coke oven which may be heated as desired by strong gas or weak gas, provided with a series of alternate horizontally elongated oven chambers and heating

walls therefor, each of said walls having vertical heating flues, separate cross-over conduits directly connecting the tops of flues of alternate heating walls only, a plurality of regenerators extending longitudinally of and below the oven chambers and connected to the heating flues and means for connecting the regenerators with flues of successive heating walls, so that the flow in more than two adjacent regenerators may be in the same direction simultaneously.

7. A regenerative coke oven provided with a series of alternate horizontally elongated oven chambers and heating walls therefor, each of said walls having vertical heating flues, separate cross-over conduits connecting the tops of flues of alternate heating walls only into independent heating flue systems, means for supporting the oven above the ground, the ovens having accessible passage-ways underneath, regenerators for the oven arranged in the direction of the oven chambers and between the soles of the oven chambers and the ceilings of the accessible passageways, and vertical pipes for supplying strong gas to the flues of the flue systems, said pipes extending from the passageways underneath the oven, to the heating flues.

8. A regenerative coke oven provided with a series of alternate horizontally elongated oven chambers and heating walls therefor, each of said walls having vertical heating flues, separate cross-over conduits connecting the tops of flues of alternate heating walls only into independent heating flue systems, means for supporting the oven above the ground, the ovens having accessible passageways underneath, regenerators for pre-heating air and regenerators for preheating gas extending in the direction of the oven and arranged between the soles of the oven chambers and the ceilings of the accessible passageways, and vertical pipes for supplying strong gas to the flues of the flue systems, said pipes extending from the passageways underneath the oven to the heating flues.

9. A regenerative coke oven provided with a series of alternate horizontally elongated oven chambers and heating walls therefor, each of said walls having vertical heating flues, separate cross-over conduits directly connecting the tops of flues of alternate heating walls only into independent heating flue systems, regenerators extending longitudinally of and below the oven chambers and connected to the flue systems, and separate means for supplying gas to each of the flues.

In witness whereof, I have signed my name to this specification.

CARL OTTO.
